ADJUSTABLE DIE SQUARE

Joseph Rimmel, Los Angeles, Calif.

Application May 11, 1953, Serial No. 353,947

5 Claims. (Cl. 33—75)

1

This invention relates to an adjustable die square, and particularly to that type of square adapted to gauge the angle of inclination or taper of a conical die opening.

In manufacturing a blanking die, it is customary to form the die with a vertical hole or opening which is cylindrical at its upper portion but which fans out a short distance below the upper die surface to form a frusto-conical wall. It is essential to the proper operation of the die that the angle of inclination or taper of this frusto-conical wall be that which is best suited for the type of blanking to be performed. Thus, for one type of blanking operation, the angle of inclination or taper should be, for example, one-fourth degree from the vertical, while for another type of operation the proper angle may be one and one-half degrees. Not only is it important that the angle be the one best adapted for the particular operation, but the frusto-conical wall of any given opening must be uniform regardless of the radial position or location at which a gauge reading is taken. Although presently known die squares are adapted to aid the machinist in manufacturing a blanking die of the type indicated, such squares are not sufficiently accurate to insure that the taper of the frusto-conical surface will be exact within the necessary limits, and are further deficient in that they may not be locked with sufficient rigidity at the proper setting for the die being formed.

In view of the above factors characterized in the field of die squares, it is an object of the present invention to provide an adjustable die square constructed so that the pivotal mounting for the gauge arm may be made accurate within extremely close limits, and so that the gauge arm may be effectively locked in any pivoted position without disturbing its setting.

Another object of the invention is to provide a die square embodying scale and clamping means for accurately positioning the gauge arm at a particular angularity relative to the body of the gauge, and constructed to facilitate sighting along the arm after its engagement with the tapered die surface.

These and other objects and advantages of the invention will be more fully set forth in the following specification and claims, considered in connection with the attached drawing to which they relate.

In the drawing:

Figure 1 is a front elevational view illustrating the die square as employed in gauging the frusto-conical opening in a die;

2

Figure 2 is a top plan view of the showing of Figure 1;

Figure 3 is a vertical section along line 3—3 of Figure 1 and as viewed in the direction of the arrows;

Figure 4 is a vertical section along line 4—4 of Figure 1;

Figure 5 is a horizontal section taken at line 5—5 of Figure 1 and illustrating the dowel means 10 for aligning the clamping block and for pivotally mounting the gauge arm; and

Figure 6 is an exploded perspective view showing the manner of mounting the clamping member and gauge arm on the base block.

Referring to the drawing, the die square is seen to comprise an elongated rectangular base block 10, a clamping plate 11 mounted on the base block, and a pivotally mounted gauge arm 12 extending transverse to the base. As indicated in Figures 1 and 2, the lower edge of base block 10 is adapted to rest on the upper surface 13 of the die 14 being formed, the gauge arm 12 then extending downwardly into the hole or opening 15 in the die. The hole 15 is formed 10 with a frusto-conical wall 17 at its lower portion, the wall 17 normally merging with a cylindrical wall 18 a short distance below the upper die surface.

The front face of base block 10 is shaped, relatively adjacent one end of the block, with a vertical groove 20 which permits, as best shown in Figure 2, the operator to sight along one edge of gauge arm 12. Groove 20 forms the inner boundary of a mounting face 21 (Figure 6) extending 30 from the groove to the adjacent end of the block. In addition to the vertical groove 20, a pair of horizontal grooves 22 are provided on the front and rear portions of the block, remote from mounting face 21, to facilitate manipulation of 35 the die square by the operator.

The clamping plate 11 is generally rectangular in shape and has, in general, the same edge dimensions as the mounting face 21 over which it is adapted to fit. The inner vertical edge of 40 clamping plate 11, adjacent groove 20, is rectangularly cut out for approximately half the thickness of the plate and over a major portion of its width. A relatively thin portion 23 of clamping plate 11 is thus formed which, as shown 45 in Figure 5, overhangs mounting face 21 and is spaced from it to define a vertical groove 24 adjacent groove 20. The bottom of groove 24 is 50 formed by the relatively thick portion 26 of the clamping member, this portion being adapted to 55

be connected to base block 10 as will next be described.

According to the invention, the thick portion 26 of clamping member 11 is provided at its center with a dowel hole 28 (Figure 6), and adjacent its ends with a pair of threaded holes 29 and 30 in vertical alignment with the dowel hole. The end portion of base block 10 is then provided with correspondingly located holes, none of which is threaded, and a dowel 31 inserted through hole 28 and the corresponding hole in the base block. A pair of Allen head screws 32 and 33 are then inserted through the base block holes and, respectively, into the threaded holes 29 and 30, the heads of the screws being seated in suitable recesses in the base block as shown in Figure 4. The dowel 28 cooperates with a second dowel 34 in maintaining clamping plate 11 in a predetermined aligned condition relative to the base block 10. The dowel 34 is inserted, prior to the positioning of screws 32 and 33, through a hole 36 (Figure 3) in clamping plate portion 23, through a hole 37 in gauge arm 12, and into a corresponding base block hole. It will be noted upon reference to Figures 1 and 6 that dowels 31 and 34 extend perpendicularly of block 10 through its longitudinal axis. As viewed from the front, the dowels and screws form a T arrangement, with the screws 32 and 33 forming the arms of the T and the dowels 31 and 34 the stem.

The dowel 34 not only aids in the aligning of clamping plate 11, but it also serves as the pivot for the gauge arm 12. The gauge arm comprises a downwardly extending thin straight blade portion 39 having a beveled outer edge 40 adapted to engage frusto-conical wall 17, and a relatively wide flat mounting portion 41 disposed in vertical groove 24 and pivotally associated with dowel 34, the latter extending through the hole 37. The corners of mounting portion 41, opposite the blade 39, are cut off at 42 and 43 to provide clearance permitting substantial pivotal movement of the blade in groove 24. Such pivotal movement may be effectively prevented, however, upon tightening of screws 32 and 33, the gauge arm mounting portion 41 being somewhat thicker than the width of groove 24 so that a clamping action results between face 21 and clamping plate 11.

The invention further provides means for accurately indicating the angle between gauge arm 12 and base block 10. These means comprise a scale 45 provided on the upper edge 46 of clamping portion 23, the edge 46 being cut away, arcuate, and beveled for this purpose. Markings 45 cooperate with a sharp indicator edge 47 formed between the angled-off corner 42 of the gauge arm, and the upper gauge arm end 48 which is arcuate to correspond to edge 46. The location of hole 37 through mounting portion 41 is such that edge 48 is spaced slightly above the scale 45, so that the operator may clearly observe the position of indicator edge 47 with relation to the markings or scale 45. The scale 45 may read in half degrees, so that the angular position of the gauge arm and the block may be determined with great accuracy. In addition, a vernier scale may be provided on edge 48 if desired. It will be noted that the scale portions of the present device are protected from damage in the event of dropping, etc., since they are primarily disposed in a recess or below the upper edge of block 10.

It is a feature of the invention that the dowels 31 and 34, and the holes adapted to receive them,

are formed with extreme accuracy, the tolerance being on the order of .005 inch. A light press fit is effected between the dowels and base 10, and a slip fit is effected between the dowels and the elements 11 and 12.

The extremely accurate forming of dowels 31 and 34, and cooperating holes, has the twofold effect of accurately locating clamping plate 11 with respect to base block 10, so that the scale 45 on the clamping plate will give true reading of the angular position of the gauge arm, and of preventing any shifting at the pivot between dowel 34 and gauge arm 12. The use of dowels in the manner indicated further assures that the markings 45 will give a true reading of the gauge arm position even when the screws 32 and 33 are relatively loose as is the case during pivoting of the arm.

In the operation of the die square, let it be assumed that the hole 15 has previously been bored in die 14, and that it is desired to test whether the wall 17 is inclined to the desired angle. The screws 32 and 33 are then loosened to permit free pivoting of gauge arm 12, and the gauge arm is pivoted on dowel 34 until edge 47 registers with the scale marking corresponding to the desired inclination of wall 17. Screws 32 and 33 are then tightened to draw clamping plate 11 against mounting face 21, so that gauge arm portion 41 is locked between clamping plate portion 23 and the base block. While the gauge arm is being locked at the desired position, there is no tendency for the arm to be rotated since there is no shearing or pivoting force acting on gauge arm mounting portion 41. It is then merely necessary for the operator to insert blade 39 of gauge arm 12 in the hole 15, as shown in Figure 1, and shift the base block 10 until beveled edge 40 is in engagement with wall 17. The operator then sights, as shown in Figure 2, along edge 40 to see whether any light appears between the blade and die, it being known that the hole 15 is perfectly formed when the full length of the blade engages die surface 17. During the sighting operation, the vertical groove 20 in block 10 permits the operator to better inspect the meeting portions of blade 39 and wall 17 for the presence of light, the edge 40 being disposed to overhang groove 20 as best shown in Figure 5.

If desired, the arm may be set at ninety degrees to the base, and the gauge employed as a right angled square.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. An adjustable die square, comprising an elongated base block adapted to rest on the surface of a die, a gauge arm pivotally mounted transversely of said base block and in flatwise engagement with one of its faces, a clamping plate disposed in flatwise engagement with the side of said gauge arm remote from said base block, said clamping plate having scale means thereon for indication of the angle between said gauge arm and base block, a pair of dowels extending through apertures in said clamping plate and base block to align said clamping plate rela-

tive to said base block, and separate means to draw said clamping plate toward said base block for clamping of said gauge arm in a given angular position.

2. The invention as claimed in claim 1 wherein one of said dowels is the pivot for said gauge arm.

3. An adjustable gauge for determining the taper of blanking die openings, which comprises an elongated rectangular base block adapted to rest edgewise on the surface of a die, said block having a transverse sighting groove relatively adjacent one end of its forward face, a clamping plate having a first portion adapted to rest on said one end of said forward face, and a second portion spaced from said forward face to form a mounting groove adjacent said sighting groove, a gauge arm having a flat wide portion disposed in said mounting groove and a thin straight portion extending transversely of said base block for insertion into a blanking die opening, one edge of said gauge arm being beveled and overhanging said sighting groove, a first dowel extending through said second clamping plate portion, said flat wide gauge arm portion and said

20
25

base block to provide a pivotal mounting for said gauge arm, a second dowel extending through said first clamping plate portion and said base block, said second dowel cooperating with said first dowel in aligning said clamping plate relative to said base block, scale means on said clamping plate and gauge arm, and means to tighten said clamping plate into locking engagement with said base block.

4. The invention as claimed in claim 3 wherein in said tightening means comprises a pair of screws inserted through said base block and threaded into said first clamping plate portion on opposite sides of said second dowel.

5. The invention as claimed in claim 3 wherein in said scale means comprises a scale formed on one end of said second clamping plate portion, said one end being recessed back from the corresponding edge of said base block.
